SMOKE HOUSE

Filed April 25, 1927

UNITED STATES PATENT OFFICE.

MAX RIND, OF SEATTLE, WASHINGTON.

SMOKEHOUSE.

Application filed April 25, 1927. Serial No. 186,336.

This invention relates to improvements in smoke houses, particularly of the type employed for curing meat, fish and like commodities by subjecting the same to a dense smoke or smudge from suitable combustibles, and aims primarily to provide a smoke house especially designed to use any kind of fuel for maintaining a smudge to cure the commodity placed therein and wherefrom the noxious combustion products of the fuel are carried off without contacting with or contaminating such commodity.

Contemplated by the present invention is a smoke house embodying a combustion chamber or fire box; a smudge chamber separated and sealed from said fire box; a curing or smoking chamber for the commodities to be cured communicating with said smudge chamber; a grating or grille separating the smudge and curing chambers; a flue for combustion products leading upwardly from the combustion chamber through the smudge chamber; a transversely disposed super-heating flue wherewith the combustion chamber flue is connected which extends through and projects at one end thereof from the smudge chamber; a flue for the smoke from the smudge chamber leading from the upper end of the curing chamber; means for supporting within the curing chamber the commodities to be treated; and means to permit of rapid and ready access to the several chambers of the smoke house, all of which are important features of the invention and are to be correlated in the broad aim of enhancing the efficiency of the apparatus for general use.

The above, and additional features and objects which will be more specifically treated are attained by such means as are shown in the accompanying drawings, described in the following specification and then more clearly pointed out in the claims, which are appended hereto and form part of this application.

With reference to the drawings, in which there is illustrated one embodiment of the invention, and throughout the several views of which like characters of reference designate similar parts:

Figure 1 is a longitudinal vertical medial section of a smoke house comprehended by the present invention, and

Fig. 2 is a fragmentary vertical transverse section of the same taken through 2-2 of

Fig. 1, certain parts thereof being shown in elevation for clarity of illustration.

Before taking up the detailed description of the drawings, a general exposition of the specific purposes, functions and advantages of the smoke house evolved by the present invention will be undertaken, which, while it is primarily and especially designed for smoking or curing meat and fish is also adaptable and suitable for treating other commodities in a like manner when necessary or desired. Heretofore, it has been customary in fabricating a smoke house to construct the same with a common smudge and curing chamber only, which necessitated burning fuel having no noxious fumes or gases to contaminate the commodity being cured, actual experience has demonstrated in many instances that such methods are inconvenient, wasteful and inefficient. Wherefore, it is a primary object of the present invention to fabricate a smoke house having a fire box or combustion chamber separated and sealed from the intercommunicating smudge and curing chambers thereof, wherein any kind of fuel may be burned such as coke, coal, oil, gas or the like, for igniting and maintaining a smudge of suitable combustibles within said smudge chamber, and wherefrom the noxious gases or fumes from said fuels are carried off in such a manner as to prevent the same from coming in contact with the commodity being treated in order that the latter may not be contaminated or detrimentally affected thereby, as will be manifest and apparent. A further and essentially important feature of the present invention is to produce and maintain a smoke house smudge in a more convenient, economical and efficient manner than has heretofore been attained. In the present instance the smoke house disclosed is equipped with oil burning apparatus, but, it is to be understood that other fuels may be used, without departing from the spirit of the invention or the benefits derivable therefrom, the present showing being merely by way of illustration.

Beginning the more detailed description of the apparatus by reference to the drawing, the numeral 3 indicates a building having a basement floor 4 and a main floor 5. Installed within the building 3 are a series of vertically disposed smoke houses 6 fabricated in accordance with the invention, which smoke houses

are supported or rest upon the basement floor 4 and extend upwardly therefrom through the main floor 5, and inasmuch as the smoke houses are identical in construction, a description of one will suffice for all.

The smoke house 6 is sub-divided into a series of chambers comprising a brick-lined combustion chamber or fire box 7, a smudge chamber 8 and a curing or smoking chamber 9. The combustion chamber 7 and smudge chamber 8 are separated from each other by a horizontally disposed brick wall 10 or by a metal plate and to effect a positive sealing and separation of such chambers from each other, a layer of fire cement 11 is spread upon the upper surface of the separating wall 10, whereat it also serves and functions as a floor for the smudge chamber 8.

Mounted upon the forward wall of the combustion chamber 7 in any convenient manner is an oil burner 12, of any well known type, the discharge nozzle or burner tip 13 of which extends into said combustion chamber through an aperture 14 formed in said forward wall, as illustrated more clearly in Fig. 1. Leading upwardly from the rear of the combustion chamber 7, substantially midway its width, is a flue 15 for the combustion products of the oil burner 12, said flue having its lower end embedded and sealed within the brick wall 10, wherefrom it extends upwardly through the smudge chamber 8 and at its upper end is curved forwardly and rigidly connected to an enlarged transversely disposed flue 16, which extends through and is common to all of the smudge chambers of the series of smoke houses, said flue 16 being primarily designed and intended to utilize the heat of the combustion products passing therethrough for superheating the smudge chamber 8 and materially increasing the temperature of the curing chambers associated therewith. The discharge end of the flue 16 extends beyond the end smudge chamber 8 of the series and is connected to a chimney, not shown. Obviously, therefore, the combustion products from the several combustion chambers cannot enter any of the correlated smudge chambers thereof, to contaminate the commodities suspended in the curing chambers.

The numeral 17 represents a mass of combustible matter, such as saw dust, or other suitable woody matter, disposed upon the floor of the smudge chamber 8, which mass is ignited and maintained in a smoldering state by the oil burner 12. An opening 18 formed in the forward wall of the smudge chamber 8 and normally closed by a door 19 provides ready and convenient access to said smudge chamber for replenishing the same with combustible matter.

Interposed and suitably supported between the smudge chamber 8 and the curing or smoking chamber 9 for separating the

same, while permitting of ready communication therebetween, is a grating or grille 20, which latter is preferably disposed in the horizontal plane of the main floor 5, and serves and functions to intercept any of the suspended commodities being treated in the curing chamber, which may accidentally drop from their supports and prevent same from falling into the smoldering mass of combustibles 17, as will be obvious and apparent.

Centrally and fixedly secured to the rear wall of the curing chamber 9, adjacent its upper end and extending perpendicularly therefrom beyond the forward wall of said chamber, is a track 21 rigidly secured at its opposite or outer end to a vertically disposed support 22. Suspended from and running upon the track 21 is a carriage or carrier 23, of any well known type, provided with a plurality of commodity supporting rods 24, upon which are hung the commodities 25 to be treated. A double door 26 hingedly mounted upon the forward edges of the vertical side walls of the curing chamber 9, serves and functions thereat, as a forward wall for the same, while permitting of ready and convenient access thereto for the rapid positioning of the carriage 23 therein and its expeditious removal therefrom. The adjacent or opposing vertical edges of the halves of the door 26 are notched to form an opening 27, wherethrough the track 21 extends when said door is closed. Leading from the upper end of the curing chamber 9, to the chimney with which the flue 16 is connected, is a flue 28, wherethrough the smoke from said chamber is discharged into said chimney.

In the operation of the herein described apparatus the wall 10 is first heated substantially to a red heat by the oil burner 12, whereupon the saw dust or other suitable combustible matter is fed into the smudge chamber 8 and is ignited therein by said heated wall 10, to thus create a dense smoke or smudge, which rises therefrom and passes upwardly through the grating 20 to completely fill the curing chamber 9, so that the untreated commodities 25 hung therein are surrounded and subjected to the action of such dense smoke for effecting the proper curing and smoke treatment of the same. Manifestly, the combustion of the mass of saw dust or other combustible matter 17 is controlled by the oil burner 12 and actual experience has demonstrated that the best results were obtained from the apparatus of the invention when the oil burner 12 was adjusted and regulated to only heat the wall 10 sufficiently to maintain such mass 17 in a smoldering state, so that the densest smoke or smudge was obtained therefrom.

While I have herein shown and described the invention with sufficient detail to enable those skilled in the art to understand the mode of construction and the principles involved,

it is to be understood that there is no intentional limitation herein to the specific form and precise details of construction herein disclosed, except as expressly defined by the appended claims, and that various modifications of said construction may be resorted to without departing from the invention, or the benefits derivable therefrom. I also desire to have it understood that certain features of the invention herein disclosed may be employed in other combinations than these shown and described.

Having thus fully described my invention, what I claim as new and desire to secure by

15 Letters Patent is:—

1. A smoke house having an enclosed combustion chamber formed within the lower portion thereof, intercommunicating smudge and curing chambers formed within the
- 20 smoke house in superimposed relation to said combustion chamber, and means individual to said combustion and curing chambers for carrying off the products of combustion therefrom.
- 25 2. In a smoke house, in combination, a casing, an enclosed combustion chamber formed within the lower portion thereof, intercommunicating smudge and curing chambers formed within said casing in superimposed relation to said combustion chamber, a flue for the combustion chamber extending through said smudge chamber, and a flue leading from the upper end of said curing chamber.
- 30 3. In a smoke house, in combination, a casing, a horizontally disposed partition having its edges rigidly secured in airtight relation to the walls of said casing adjacent the lower end thereof to form a combustion chamber therebetween and having a layer of fire ce-

ment upon its upper side, and a horizontally disposed grating mounted within said casing substantially midway the height thereof to form superimposed intercommunicating smudge and curing chambers between said 45 partition and the upper end of said casing.

4. In a smoke house, in combination, a casing, an enclosed combustion chamber formed within the lower portion thereof and having an opening formed within one of the 50 walls thereof, an oil burner operatively mounted within said opening, intercommunicating smudge and curing chambers formed within said casing in superimposed relation to said combustion chamber, a flue 55 for the combustion chamber extending through said smudge chamber, and a flue leading from the upper end of said curing chamber.

5. In a smoke house, in combination, a casing, an enclosed combustion chamber formed within the lower end thereof, intercommunicating smudge and curing chambers formed within said casing in superimposed relation to said combustion chamber, a transverse flue 60 extending through said smudge chamber and sealed therefrom, and a flue connecting the combustion chamber with said transverse flue.

6. In a smoke house, in combination, a casing, an enclosed combustion chamber formed 70 within the lower portion thereof, intercommunicating smudge and curing chambers formed within said casing in superimposed relation to said combustion chamber and sealed therefrom, individual doors for said 75 chambers, and means within said curing chambers for supporting the commodities to be cured.

In testimony whereof I affix my signature.

MAX RIND.
